EDGAR H. MORRISON, OF VIRGINIA BEACH, VIRGINIA

PHONOGRAPH DISK RECORD

Application filed November 2, 1928. Serial No. 316,807.

The present invention relates to hubs or reinforcing centers for discs or phonograph records. Ordinarily such disks have only a central opening of the same size as the phonograph spindle and the edges of this opening are comparatively soft, being formed in the disk itself, the material of which is not hard enough to withstand wear or rough handling. As, however, in general usage this opening 10 only serves for centering the disk on the revolving table, which communicates the motion to the disk through the soft padded top, the said edges are not exposed to a great deal of wear except in the placing or receiving 15 of a record disk on the table. When, however the records are repeated over and over again on automatic replacing machines, the strain is very great and as a consequence the opening will soon be enlarged or still 20 worse, worn more on one side than on the other. Sometimes actual pockets are formed to one side of the opening so that it is impossible to properly center the disk again, but more serious still is the fact that the disks 25 do not properly set or aline on the supporting arm of the machine and as a consequence of this the machine fails to function.

It is therefore the object of my invention to eliminate these disadvantages and to supply 30 record disks with centers that will stand considerable hard usage. For this purpose I supply a hard, flanged hub or center of any suitable material, such as steel, brass, or the like, and form the disk around the same during 35 manufacture. In this manner I provide a disk center that will last the record out without any appreciable change in the size of the central opening.

For restoring records in which the central 40 opening has already been distorted, I propose to use hubs with star-shaped ends. In that case the opening in the disk is restored to circular by inserting a temporary centering piece of the type shown in Figure 6. This 45 device is a cylindrical piece of metal having

smooth or undulated edges, which are then spun, flared, or bent outwardly to grip tightly the two faces of the disk. The restored record may then be used again for a long time until the sound-producing grooves have 50 been worn out.

I am aware that clips have been used for record disks both around the periphery and in the center thereof, but they are furnished solely for the purpose of securing two single 55 record disks together so as to make a reversible unit thereof. They are moreover all placed in position after the records are finished and not during the manufacture thereof. 60

My invention is illustrated in the accompanying drawing in which—

Figure 1 is a face view of a record disk provided with a hub or bushing forming the subject matter of the present invention; 65

Figure 2 a diametrical section of Figure 1;

Figure 3 shows a face view of an ordinary record disk with a worn and distorted central opening;

Figure 4 a similar view showing the disk 70 in Figure 3 bushed and its opening restored to normal size;

Figure 5 a diametrical section of Figure 4, and;

Figure 6 is a perspective view in larger 75 scale of a reinforcing hub ready for insertion in the disk.

In Figures 1 and 2 an ordinary record disk is represented by reference numeral 10. It is provided with a central opening 12 somewhat larger than the opening in a disk of the usual kind. This opening is filled by a metallic sleeve or bushing 11 fitting tightly therein and having a flange 13 at each end sunk into the body of the disk 10 so that the 80 exposed sides of the flanges become flush with the side surfaces of the disk. It will be evident that with a bushing flanged in this manner, it would be impractical to insert it 85 after the record is otherwise finished. I 90

therefore propose to first supply the hub or bushing 11 having the flanges 13 extending radially from the ends thereof; then forming the disk around it so that it becomes embedded in the body of the disk during the process of manufacture when the disk is formed around the hub. A true center is thus provided for the disk with an opening 14 of the exact diameter to fit the table spindle of the phonograph. In case the latter now should be an automatic replacement machine the hooked finger on the lifting arm cannot possibly destroy the roundness of the central opening 14 and the usefulness of the record is thus prolonged considerably.

In the case of old records that have been already worn so as to have an enlarged, eccentric, central opening 15, as seen in Figure 3, I propose to use a bushing 16 (see Figure 6) with undulated end edges 17. In such cases the temporary piece 16 is simply inserted by hand and the prongs 17 bent outwardly against the surface of the disk on both sides, thus giving the appearance of a many-pointed star with the fingers spread out radially from the center opening 14 which is of the same diameter as the spindle on the revolving table of the machine. This construction is shown in Figures 4 and 5 where the fingers are indicated as lying flat on the side surfaces 18 of the disk and the annular portion of the bushing fits against the inner periphery 19 thereof. It is, however, evident that a counter-bore, may be provided on each side as indicated in Figure 2 in which case the star fingers also here would be flush with the side surfaces of the disk.

Instead of using a star-shaped hub or bushing, the flanges may have any other contour such as hexagonal, square, circular or the like. In that case the flanges may be spun or pressed out from the tubular sleeve.

It is understood that the invention is not limited to the details of construction here shown and described, but that these may be varied widely without departing from the spirit of the invention as defined by the claims.

What I claim as new is:

1. In a means for repairing a disk phonograph record when the center opening has been worn and distorted, a reinforcing bushing adapted to be inserted in the center opening of the disk record for cooperation with a center spindle comprising a cylindrical body portion having an internal diameter substantially the size of the center spindle, said body being provided with prongs at each end adapted to be bent at right angles to the axis of the cylindrical body into intimate contact with the opposite side faces of a disk record.

2. In a phonograph record, a circular disk and a hub for said disk forming an insepa-

rable unit therewith, the interior diameter of the hub corresponding to that of the phonograph spindle, and said hub provided with radially projecting prongs lying flat against the side surfaces of the disk.

In witness whereof, I have hereunto set my hand at Virginia Beach, Virginia, this 15th day of October, A. D. nineteen hundred and twenty-eight.

EDGAR H. MORRISON.
